United States Patent Office

Des. 195,572
Patented July 2, 1963

195,572

VALET STAND OR SIMILAR ARTICLE

Harold Gleitsman, New Rochelle, and Carl Fuerst, Bronx, N.Y., and John H. Squadra, Westport, Conn., assignors to Gleitsman's, Inc., Long Island City, N.Y., a corporation of New York

Filed Jan. 7, 1963, Ser. No. 73,060

Term of patent 14 years

(Cl. D33—8)

FIG. 1 is a front perspective view of the valet stand showing our design;

FIG. 2 is a front elevational view thereof;

FIG. 3 is a side elevational view thereof;

FIG. 4 is a bottom view thereof; and

FIG. 5 is a top view thereof.

We claim:

The ornamental design for a valet stand or similar article, substantially as shown.
